UNITED STATES PATENT OFFICE.

PAUL B. BUDAI, OF MONTGOMERY COUNTY, NEAR DAYTON, OHIO.

HYDROCARBON-BURNER.

1,331,048.

Specification of Letters Patent.

Patented Feb. 17, 1920.

Application filed June 30, 1919. Serial No. 307,669.

To all whom it may concern:

Be it known that I, PAUL B. BUDAI, a subject of the Emperor of Austria-Hungary, residing in the county of Montgomery, near 5 the city of Dayton, State of Ohio, have invented certain new and useful Improvements in Hydrocarbon-Burners, of which the following is a specification.

This invention relates to new and useful 10 improvements in hydrocarbon burners.

One of the objects of my invention is to provide a cheaply constructed and efficient burner that is adapted to be easily inserted in oil and gasolene stoves, for cooking and 15 heating purposes.

Another object of my invention is to eliminate the use of asbestos and other kinds of wicks that frequently need replacement and are apt to clog up the burner when in use. 20 Instead of these wicks, I provide a steel wool filler or atomizer that does not need replacement, it does not clog up the generating tube, and breaks up and sets in whirling motion, the oil prior to its issuance from the 25 discharge orifice.

Another object of the invention is the provision of a discharge orifice that is not difficult to drill, said orifice receiving a specially constructed pin that causes the gas to 30 issue around it in tubular form, causing it to unite with more air after it leaves the discharge opening.

Another object of the invention is to provide a channel to receive the oil which 35 comes out with the gas when too much oil is admitted to the generator tube before it is properly started, said oil being directed by said channel to a tube through which it is drawn off.

40 Another object of the invention is the provision of a lid device that may be readily removed to afford instant and easy access to the discharge orifice to loosen up the carbon around the pin therein.

45 Another object of the invention is to provide a removable trough-shaped device for priming or initially heating the generating tube, further means being provided to keep it continuously heated while in operation.

50 It is a further object of the invention to provide for this latter purpose, a manifold which is constructed in a single casting.

Other important and incidental objects will be brought out in the following specifi-

cation, and particularly set forth in the sub- 55 joined claims.

The preferred form or embodiment of my invention is illustrated in the accompanying drawings, of which Figure 1 is a top plan view of my improved hydrocarbon 60 burner. Fig. 2 is a sectional view of said burner on the line A—A of Fig. 1. Fig. 3 is a vertical sectional view of said burner on the line B—B of Fig. 1. Fig. 4 is a sectional view of the mixing chamber taken 65 on the line C—C of Fig. 1. Fig. 5 is an enlarged vertical sectional view of the outlet end of the generator tube. Fig. 6 is an end view of the same. Fig. 7 is a horizontal 70 sectional view thereof. Fig. 8 is a detail 75 plan view of the priming device. And Fig. 9 is an end view of the same.

Throughout the specification and drawings, similar reference characters denote corresponding parts.

Referring to the accompanying drawings, the numeral 1 designates a conduit or manifold casting which at its outer end terminates in a portion 2 that is preferably hook-shaped in cross section as shown in Fig. 3. 80 Provided on the top middle portion of the casting 1 is a hollow ridge or rib 3 which extends from its enlarged forward end portion to a point a short distance from its other end, forming with the latter a shoulder 4 that receives the cross portion 5 of a removable priming trough 6 preferably shaped like a tuning fork whereby each leg thereof may rest on top of the horizontal portion of the conduit 1, on a respective side 85 of the rib 3, for a purpose to be hereinafter described.

The inner wall 7 of the end portion 2 of the casting 1, is preferably vertical, containing a short distance above the level of 95 the ridge 3, an opening into which is tightly driven a flanged plug 8. The latter has provided in its end wall a discharge orifice 9 which communicates with a bore 10 in the plug that is adapted to receive the hydrocarbon mixture from a generating tube 11 which is screwed on the exteriorly threaded inner end of the plug. The other end of the generating tube 11, which is horizontally disposed, is screwed on the horizontal, tubular flanged end of a needle valve housing 12. The latter has a downwardly projecting fuel inlet end 13 and a horizontal outwardly 100 105

projecting end 14 that receives a needle valve 15 by means of which the flow of liquid fuel to the generating tube 11 may be controlled. (See Fig. 1.)

5 The downwardly projecting end 13 of the needle valve housing 12 has an annular flange 16 which rests upon the horizontal end portion of a sheet metal plate 17 that inclines downwardly to a vertical portion 10 which is firmly secured, by means of a screw 18, to the front end of the horizontal portion of the casting 1. The downwardly projecting portion 13 of the housing 12 has a reduced threaded portion 19 that passes 15 through a hole in the horizontal portion of the plate 17, a nut 20 being applied to said threaded reduced portion for the purpose of firmly clamping the outer end of the plate 17 against the flanged portion 16 of the 20 valve housing projection 13. By the means thus described, the needle valve housing 12 and inner end of the generating tube 11 are firmly supported by the inner end of the conduit casting 1.

25 Provided in the generating tube 11 is a steel-wool filler 21 which does not deteriorate like asbestos wicking or like material. Furthermore, it does not clog up the orifice 9. The liquid fuel in its course therethrough 30 is thoroughly broken up or atomized prior to its entrance to the discharge orifice 9.

As before stated, there is provided for this orifice, a pin which is preferably round with the exception of its two ends,—and 35 they are flat to act as flanges to hold said pin, which is designated by the numeral 22, in the orifice. The diameter of this pin is less than that of the orifice 9 to permit the atomized fuel a minute exit passage around 40 the pin, which causes it to issue from the orifice as a spray which assumes a somewhat tubular form. As it leaves the orifice, the fuel spray is mixed with air that is conducted to it as follows.

45 Referring to Figs. 2, 3 and 4, there is provided on each side of a horizontal channel member 23 projecting into the enlarged portion 2 of the casting 1, an air inlet passage 24 which directs the air toward the orifice 9 50 as shown by the arrows in Fig. 4. The mixture resulting from the commingled air and atomized fuel, passes around the outer end of the channel member 23 into the passage 25 as indicated by the arrows in Fig. 3, impinging against a rib 26, by which it is directed upwardly beneath a series of holes 27 provided in the top of the ridge 3 of the casting 1. As the gas, becoming ignited, 55 passes inwardly beneath the apertured ridge 3 of the casting, it supplies continuous heat to the generating tube 11 above for the purpose of keeping it at a temperature which insures a thorough vaporization of the liquid fuel that passes through the steel wool filler 60 21 therein.

For the purpose of preheating said generating tube 11 when the burner is started, the trough 6 heretofore described is employed. By means of a handle 28 that inclines outwardly from the inner end of said trough member, it may be readily placed in position on top of the horizontal portion of the casting 1, with the ridge 3 between its prong portions. The alcohol or other priming fluid which it may contain, is then ignited, with the result that the heat of combustion passes upwardly around the vaporizing tube 11 for the purpose of thoroughly preheating the liquid fuel therein, after which the heat produced from the ignited 75 gas passing upwardly through the holes 27 in the ridge 3, will heat said tube sufficiently for generating purposes as long as the burner is in operation.

If perchance any oil should pass through 85 the orifice 9 during the starting of the burner, said oil will drop upon the concave top portion of the channel member 23 from which it will fall into an outlet tube 28 screwed in the bottom of the casting 1. On 90 the bottom of the tube 28 is a petcock 29 for the purpose of draining out the oil at desired intervals. (See Fig. 3.)

Referring to Figs. 2, 3 and 4, there is provided in the top of the enlarged end portion 95 2 of the casting 1, a hole 30 that is normally closed by a lid 31. By removing this lid, ready access may be had to the pin 22 for the purpose of removing any carbon which may collect thereon.

100 After being thoroughly mixed with air in the mixing chamber before described, the vaporized fuel passes into a conduit or manifold 32 at right angles to the conduit 1. This manifold 32 communicates with a hollow circular burner 33 supported by legs 34, said burner containing a series of raised portions or ridges 36 in its top portion, said ridges being disposed around a hole in the center of the burner and being spaced a 105 sufficient distance apart and run at approximately right angles to one another, to permit air freely to circulate between them. They are near enough together, however, that should one burner ridge become extinguished, it will be immediately ignited by the surrounding ones. Provided in the ridges 36 are slots 36^a through which the gas flame issues, said slots being disposed in the same direction to permit them to be 110 readily formed by a cutter whose position need not be changed for each slot, as is the case in cutting radial slots.

115 Firmly secured by means of a screw 37 within the burner 33 is an inclined deflector 120 38 for the purpose of insuring a thorough diffusion of gas through the burner.

An additional burner 39 is provided on the right hand side of the casting 1 for use when desired. Communicating with the 130

burner 39, which is supported by legs 40, is a conduit 41 that is preferably the integral part of a valve housing 42 which receives gas from the conduit 1 through a transmission tube 43. The latter terminates at its lower end in a seat for a puppet valve 44 carried by a stem 45 threaded into a bushing 46 which is screwed into the lower threaded end of the valve housing 42. When this valve is lowered, communication is established between the tube 43 and conduit 41 through the valve housing, whereby the burner 39 will receive gas from the conduit 1 as well as the burner 38. By means of the valve 44 it is easily possible to shut off the burner 39 when it is not needed. (See Figs. 1 and 2.)

There is also provided in the burner 39 a deflector 46 which is similar to the deflector 38 in the burner 38 and which performs a similar function.

Having described my invention, I claim:

1. In a device of the type described, the combination with a gas receiving conduit, of a vaporizing tube in communication therewith, a plug inserted in the end of said vaporizing tube that communicates with the conduit, said plug containing an easily drilled discharge orifice, and a round pin of less diameter than the orifice, provided in the latter to afford a minute passage for the gas around its periphery, the ends of said pin being flattened to hold it in said orifice.

2. In a device of the type described, the combination with a gas receiving conduit having an upwardly extending enlarged end, a vaporizing tube in communication with said end, a horizontal channel member in the latter, below the outlet end of the vaporizing tube, adapted to receive unvaporized fuel from said vaporizing tube and discharge it from its outer end, and an outlet for said

fuel in the bottom of the enlarged end of the conduit below the discharge end of the channel member.

45

3. In a device of the type described, the combination with a horizontally disposed gas receiving conduit, a rib on the top portion of the latter, a vaporizing tube horizontally disposed above said rib, and a priming trough shaped somewhat like a tuning fork, to straddle said rib below the vaporizing tube.

4. In a device of the type described, the combination with a horizontally disposed gas-receiving conduit, a rib on the top portion of the latter, a shoulder formed between one end of said rib and the top portion of the conduit, a vaporizing tube horizontally disposed above said rib, and a priming trough shaped somewhat like a tuning fork, whose cross portion rests upon said shoulder and whose leg portions straddle the rib below said vaporizing tube.

5. In a device of the type described, the combination with a horizontally disposed gas-receiving conduit, a hollow rib on the top portion of the latter, containing gas issuing holes, a shoulder formed between one end of said rib and the top portion of the conduit, a vaporizing tube horizontally disposed above said rib, a priming trough shaped like a tuning fork whose cross portion rests upon said shoulder and whose leg portions straddle the rib below the vaporizing tube and a handle inclining outwardly from the inner end of said priming trough, for placing it in position on the top portion of said conduit.

In testimony whereof I have hereunto set my hand this 28th day of June, 1919.

PAUL B. BUDAI.
